UNITED STATES PATENT OFFICE.

LEWIS R. THOMAS, OF BIDDEFORD, MAINE.

COOKING-UTENSIL.

SPECIFICATION forming part of Letters Patent No. 269,488, dated December 19, 1882.

Application filed August 17, 1882. (No model.)

To all whom it may concern:

Be it known that I, LEWIS R. THOMAS, a citizen of the United States, and a resident of Biddeford, in the county of York and State of Maine, have invented certain new and useful Improvements in Iron Kettles, of which the following is a specification, reference being had to the accompanying drawing.

This invention relates to improvements in east-iron hollow ware for cooking-utensils, to be used on top of cooking-stoves, which will be hereinafter more fully described, and set forth in the claim.

The figure in the drawing is a vertical sectional elevation of a pot seated on the top of a cooking-stove, over the fire-place, with the lid removed.

A is the side extending down to the flange B, which is much lower than the bottom a of the utensil, forming an air-space, b, between the bottom and the top line of the stove C. When the lid is removed from the hole c the heated air from the fire-surface will arise and fill the air-space and come in contact with the entire bottom a of the utensil.

In the ordinary utensils for stoves the bottom is reduced in diameter and fits into the hole, and drops down nearer the fire-surface, as seen in broken lines b' in the drawing, which

in certain utensils is a disadvantage, as the bottom, coming in contact with the fuel, is soon burned out by reason of the sulphur in the coal.

Another great advantage in my improvement is that it is not necessary to lift the utensil to move it on the stove, as it can be slid along without lifting. The improvement is so simple as not to require any further description.

I am aware that hollow earthenware utensils have been made with a flange below the bottom, and some metal utensils have partial flanges.

I am also aware of the construction shown in Patent No. 172,538, of January 18, 1876, and such I do not claim; but

What I do claim, and wish to secure by Letters Patent of the United States, is—

The combination of the hereinbefore described kettle with a pot-hole of less diameter, the relation of the kettle-flange to the stove-hole being such that the kettle is prevented from entering the hole, and at the same time provides a combustion-chamber in the base of the kettle above the top plate of the stove, substantially as set forth.

LEWIS R. THOMAS.
